UNITED STATES PATENT OFFICE.

MERCED LEDESMA AND ADOLFO ACOSTA, OF EL PASO, TEXAS.

CLEAN-OUT ATTACHMENT FOR THE RETENTION PIPE AND RETENTION VALVE OF AN AIR-BRAKE SYSTEM.

Application filed August 4, 1924, Serial No. 729,996. Renewed November 30, 1925.

To all whom it may concern:

Be it known that we, MERCED LEDESMA and ADOLFO ACOSTA, citizens of the United States, residing at El Paso, in the county 5 of El Paso and State of Texas, have invented certain new and useful Improvements in a Clean-Out Attachment for the Retention Pipe and Retention Valve of an Air-Brake System, of which the following 10 is a specification.

This invention relates to a means for cleaning out the retention pipes and the retention valves associated therewith of an air brake system and has for its principal object to provide a simple and efficient device which may be readily and easily attached in position for use.

Another important object of the invention is to provide a clean-out attachment 20 which is adapted to be connected at one end to the branch pipe of the train line and at its opposite end to the retention pipe whereby a direct flow of compressed air will pass from the train line into the retention pipe 25 for cleaning the same and the valve associated therewith in a comparatively simple and efficient manner.

A further object of the invention is to provide a clean out attachment of the 30 above mentioned character, which is simple in construction, inexpensive, strong and durable and furthermore adapted for the purposes for which it is designated.

Other objects and advantages of this invention will become apparent during the course of the following description.

In the accompanying drawing forming a 40 part of this specification and in which like numerals designate like parts throughout the same:

Figure 1 is a side elevation of our improved cleaner attachment showing the same in use, and

Figure 2 is a view partly in elevation and 45 partly in section of the improved clean-out attachment.

Ordinarily the retention pipe of an air 50 brake system has one end connected to the exhaust port of the triple valve 2 and the retention pipe 1 terminates in the upwardly disposed portion 3, the upper end of which carries the usual manually controlled retention valve 4. As the construction of the retention valve may be of any well known 55 type, well known in the art, a further de-

tailed description thereof is not thought necessary. The retention valve 4 is located at a point adjacent the top of each of the cars and the purpose of the retention pipe and the retention valve is to provide a means for 60 retaining a working pressure in the brake cylinder 5 of the air brake system while the auxiliary reservoir 6 is being recharged. The amount of pressure retained in the 65 brake cylinder depends upon the weight and load of the car. The train pipe of the air 70 brake system is designated at 7 in the drawing and the same is connected to the triple valve 2 by means of the branch pipe 8 in the manner well known in the art.

For the purpose of cleaning or blowing 75 out the retention pipe and the retention valve, we provide an attachment which comprises a tubular section of flexible material such as is illustrated at 9, a nipple 10 being 80 arranged in one end of the flexible pipe 9 and adapted for communication with the branch pipe 8 when the latter is detached from the triple valve 2. A similar nipple 11 is arranged in the opposite end of the 85 flexible pipe and has communication with a suitable union or coupling 12 which is adapted to be connected to the end of the retention pipe 1 after the same has been detached from the triple valve 2 in the manner clearly illustrated in Figure 1 of the drawing. It is of course understood that the nipples 10 and 11 respectively are supported in the ends of the flexible pipe 9 by 90 means of any suitable hose clamps or the like illustrated at 13.

With the parts arranged as shown in Figure 1 of the drawing, the air under pressure passing through the train line 7 will be discharged through the branch pipe 8, 95 through the flexible hose line and through the retention pipe and the retention valve associated with the upper end thereof. This will enable the retention pipe and valve to be readily and easily cleaned so that the same 100 will be permitted to properly function when attached to the exhaust port of a triple valve 2 by means of the pipe 14. A blow out attachment for cleaning the retention pipe and retention valve associated therewith may be readily and easily attached in position without the loss of any considerable length of time or labor and may furthermore be readily detached so as to enable the retention pipe to be connected to the triple valve 105 110

as well as enabling the train line to be connected thereto.

The simplicity in which our device is constructed enables the same to be manufactured at a very low cost and will at all times be positive and efficient in carrying out the purposes for which the same is designed.

While we have shown the preferred embodiment of our invention, it is to be understood that various changes in the size, shape and arrangement of parts may be resorted to without departing from the spirit of the invention and the scope of the appended claims.

Having thus described the invention, what we claim is:—

1. The combination with an air brake system including a train line and the retention pipe and retention valve associated therewith, of a connection between the train line and the retention pipe for forcing the air under pressure in the train line to the re-

tention pipe and the retention valve for cleaning out the same.

2. The combination with an air brake system including a train line and the retention pipe and retention valve associated therewith, of a connection between the train line and the retention pipe for forcing the air under pressure in the train line to the retention pipe and the retention valve for cleaning out the same, said connection comprising a flexible hose detachably connected to the train line and the retention pipe at its respective ends.

3. In combination with an air brake system including the retention pipe and the retention valve associated therewith, of means for facilitating the cleaning out of the retention pipe and the retention valve.

In testimony whereof we affix our signatures.

MERCED LEDESMA.
ADOLFO ACOSTA.
